TIP SANDER FOR BILLIARD OR POOL CUE

William H. Sheffer, Riverside, Ill., assignor to Tweeten Fibre Company Inc., Chicago, Ill., a corporation of Illinois

Filed Oct. 30, 1967, Ser. No. 9,206

Term of patent 14 years

U.S. Cl. D37—1
Int. Cl. D21—04

FIG. 1 is a perspective elevation view of a tip sander for billiard or pool cue embodying the design of the present invention;

FIG. 2 is a front elevation view of the tip sander for billiard or pool cue;

FIG. 3 is a rear elevation view of the tip sander for billiard or pool cue;

FIG. 4 is a sectional elevation view taken approximately along line 4—4 in FIG. 2 fragmentarily shown for convenience of illustration; and

FIG. 5 is an exploded view of the principal components of the tip sander for billiard or pool cue.

I claim:

The ornamental design for a tip sander for billiard or pool cue, substantially as shown and described.
